APPARATUS FOR EXTRACTING SOLUBLE SUBSTANCES.

1,282,407.

Specification of Letters Patent. Patented Oct. 22, 1918.

Application filed October 3, 1917. Serial No. 194,479.

To all whom it may concern:

Be it known that I, WILLIAM E. GARRIGUES, a citizen of the United States, residing at New Orleans, in the parish of Orleans and State of Louisiana, have invented certain new and useful Improvements in Apparatus for Extracting Soluble Substances, of which the following is a specification.

My invention relates to apparatus for extracting soluble substances, such as grease, from various materials containing the same, by means of suitable solvents, such, for example, as gasolene or naphtha, and recovering the solvent.

In the process, practised in my apparatus the material containing the soluble substance and the solvent are first agitated together and the solvent with the dissolved substance drawn off as fully as possible. This may be accomplished, for example, in a horizontal rotary extractor, running the solvent in at one end and drawing off the solution at the other end, through a filter, until the soluble substance is all withdrawn. A draw-off pipe may then be connected to the bottom of the extractor and a considerable proportion of the remaining solvent therein drawn off.

In such an operation, a certain amount of the solvent remains within the mass of material, caught between the particles thereof and adhering thereto. My invention recovers this residue by introducing hot gas, such as steam, entirely within the mass of material, while thoroughly agitating the mass, and at the same time providing a connection for carrying off the hot gas or steam with the solvent volatilized by the heat thereof. This operation may be carried out in a horizontal rotary extractor by rotating the same and connecting it axially to a condenser and vacuum-pump, while at the same time introducing steam into the mass of material in the vessel. This may be done, for example, by the provision of a plurality of perforated steampipes within the extractor and a valve so constructed as to always deliver steam into the lower pipes, which are within the mass of material. The pressure within the mass will thus be greater than that in the space above the material, and as the material is tossed about the liquid matter remaining in the mass will readily be volatilized and carried out of the same with the steam to the condenser. In such a system, a series of closed heating pipes should

also be located within the extractor, to obtain the best results, to prevent condensation of the steam in the mass of material.

In order that my invention may be more clearly understood, attention is hereby directed to the accompanying drawings, forming part of this application and illustrating a form of apparatus embodying my invention.

In the drawings, Figure 1 represents a sectional longitudinal view through a horizontal rotary extractor, certain parts being shown in elevation, and Figs. 2 and 3 are respectively cross-sections taken on lines 2—2 and 3—3 of Fig. 1.

Referring to the drawings, my process is preferably carried on, as stated, by means of a horizontal rotary extractor, such as that illustrated at 1, which may be provided with peripheral rails 2 and 3, which rest in contact with rollers, such as 4, 4 and 5, the extractor having a driving gear 6 which meshes with a driving pinion 7. Suitable manholes and covers therefor, 8, are provided for filling the extractor, and a suitable screen is provided at one end, which may comprise a perforated plate with a brass wire screen and filter-cloth, illustrated, generally, at 9, retained by means of a suitable retaining ring 10. An end member 11 is provided beyond the screen, having an axial opening therein, to which is connected a pipe 12 provided with a valve, such as the gate-valve 13 shown. The pipe 12 is connected, through a stuffing-box indicated at 14, to a connection 15 provided with a valve, such as the gate-valve 16, leading to a condenser, and, when some types of condenser are used, to a vacuum pump.

A suitable draw-off connection is indicated at 17, having a coupling 18 adapted to be connected to a nipple 19 provided with a valve 19', and connected to the lower portion of the space 20 between the screen 9 and end 11 of the extractor when the latter is not rotating. Connection 17 may be connected through a T 21 to a still (not shown) for the naphtha or other solvent used. A connection 22, provided with a valve 23, may also be provided, extending from T 21 to the condenser connection 15.

The solvent may be introduced axially into the extractor at the opposite end of the apparatus through a pipe 24 provided with valve 24', T 25 and pipe 25'. This pipe 25' 110

extends a short distance within the end closure 26 of the extractor and is surrounded by a valve construction comprising an inner cylindrical member 27 secured to pipe 25' at its outer end by a bushing 28, which may be screwed on the pipe. At the other end of member 27, a radially extending portion 29 is secured to pipe 25', as by a threaded connection, an annular space 30 being provided 10 about pipe 25' between bushing 28 and the opposite end closure 29 of member 27.

An outer casting or member 31 surrounds member 27 and is provided with lugs 32 secured to the end member 26 of the extractor to rotate therewith. Rotation between members 27 and 31 may be provided for by a suitable gland 33, secured to outer valve-member 31 and provided with a suitable packing 34.

20 Suitable hot gas, such as steam, may be introduced through pipe 35, provided with a valve 36, into the space 30. A plurality of perforated pipes 37 are provided within the extractor, for distributing this hot 25 gas within the mass of material in that portion of the extractor which is lowermost at any moment. Pipes 37 of any suitable number, such as six, extend longitudinally through the extractor at suitably spaced 30 intervals and may be secured in position by means of U-bolts 38 extending about the pipes and secured to L-irons 39 mounted on the interior of drum 1. At the end of the extractor adjacent the rotary valve, pipes 37 35 are bent radially as shown at 37' and screwed through radial pipe taps in the outer member 31 of the valve.

The inner or stationary member 27 of the valve is cut away for a short distance axially thereof, at its lower portion, as shown 40 in Fig. 3, to provide a steam or hot gas space 40, the lower wall of which is formed by the interior of the rotary valve-member 31 and the outer walls of which are formed 45 by radii of a circle making an angle with each other which is preferably less than 180 degrees. Pipes 37' connect with space 40 when they are at the bottom of the drum, and are cut off therefrom when they are in 50 the upper portion of the drum.

A series of closed heating pipes is also preferably mounted within the extractor and may comprise a plurality of longitudinal pipes 41 connected at the end distant from 55 the rotary valve to a circular pipe 42. At the opposite end, pipes 41 are bent radially inwardly, as shown at 41', and are tapped through the outer member 31 of the valve to constantly connect, by means of an annular space 43, with the steam space 30 of 60 the valve. A return pipe 42' extends from pipe 42 out through pipe 25', and, if desired, through a suitable stuffing-box, as shown.

65 The operation of the described apparatus

will now be apparent. The extractor is partly filled with a material in loose condition, containing the soluble substances to be extracted, and the solvent, preferably pre-heated, is continuously run in through pipe 70 25', while the extractor is rotated, coupling 18 being disconnected, valves 13 and 23 open, and 16 closed, until the extraction is completed, the solvent with soluble substance dissolved therein flowing through T 21 to 75 the still until all of the soluble substance has been thus removed. The extractor is then stopped, coupling 18 connected thereto, valves 13 and 23 closed, and as much of the solvent drawn off through pipe 17 and T 80 21 as possible. Coupling 18 is now disconnected, the extractor again rotated, valve 36 opened to permit steam to flow into pipes 37 and 41, and valves 13 and 16 opened. Steam now flows through the perforations in 85 the pipes 37 which are for the moment lowermost, into the mass of material at the bottom of the extractor, those pipes 37, which are for the moment located in the open space above the mass of material, not delivering any steam into such space. The closed system of pipes 41-42 will also be filled with steam and thereby heated, preventing the condensation of the steam in the material. The constant turning over or agitation of the material permits the permeation 90 of the entire mass by the steam and the ready escape of the steam from the mass. The solvent is quickly volatilized by the heating and is carried off by the steam 100 through pipe 15 to the condenser.

The arrangement by which the steam or other hot gas is discharged within the mass of material and not at all in the space above the material prevents the waste which would 105 occur if this empty space were uselessly filled with steam. Another effect of this arrangement is also to be observed, namely, that discharging the steam or hot gas within the mass of material only, causes the vapor pressure within the mass to be greater than that in the space unoccupied by the mass, so that the gas, with the volatilized solvent and any particles of the same which may remain liquid, entrained therein, will rapidly rise 110 from the mass and escape through connection 12.

It will be noted that my invention is not limited to the details of mechanism described, but that the same is as broad as is 120 indicated by the accompanying claims. The chief point of novelty in my described process, carried out by apparatus of the character described may be considered broadly as consisting in removing the last portion 125 of the solvent, which it is impossible to draw off from the mass in a process such as described, by violently agitating the mass in a rotating vessel partly filled with the same, while producing heat within the mass 130

and producing a condition of vapor pressure within the mass greater than that in the space above the same. In the following claims, the term "hot gas" will be used to indicate steam and its equivalents. Other points of novelty consist in a continuous operation of extraction in a horizontal rotary extractor, fresh solvent continuously flowing in during the rotation and solution continuously being drawn off through a vertical filter. The filter cloth is kept clean by the rotation, and the steam and vapor are screened as well as the liquid, thereby preventing the carrying over of any solid material to pipe 12. The use of a horizontal rotating drum has manifold advantages over a vertical extractor, including economy of power, the possibility of using a drum as long as is desired, etc.

20 What I claim is:

1. Extracting apparatus comprising a horizontal rotary drum, spaced perforated pipes secured therein extending lengthwise thereof and radially at one end, a valve at 25 said end having an inlet or solvent therethrough, a stationary member mounted about said inlet and having an interior space, opening through the exterior of the member at one portion thereof, a gas inlet connected to 30 said space and an outer member secured to said drum to rotate therewith, surrounding said stationary member, and having the ends of said pipes extend therethrough, said pipes being adapted to open into said space 35 when in the rotation of the drum they occupy the lower portion of the drum, and to cut off therefrom when they occupy the upper portion of the drum.

2. Extracting apparatus comprising a 40 horizontal rotary drum, spaced perforated pipes secured therein extending lengthwise thereof and radially at one end, a valve at said end having a stationary member provided with an interior space, opening 45 through the exterior at one portion thereof, an inlet pipe connected with said space, and a member secured to the drum to rotate therewith, adapted to cover the said opening in the stationary member, the ends of said 50 pipes extending at spaced intervals through said rotatable member, and registering with

said opening when said pipes occupy the lower portion of the drum, and cut off therefrom when they occupy the upper portion of the drum.

3. Extracting apparatus comprising a horizontal rotary drum, spaced perforated pipes and a series of closed pipes secured therein, and a valve at one end of the drum, comprising a stationary and a rotary member, provided with an interior space having an inlet pipe connected therewith, said closed pipes being connected to said valve to always open into said space, and said perforated pipes being connected to said valve 60 to open into said space only when they occupy the lower portion of the drum, during the rotation thereof.

4. Extracting apparatus comprising a horizontal rotary drum, spaced perforated 70 pipes secured therein, and a valve at one end of the drum, comprising a stationary and a rotary member, provided with an interior space having an inlet pipe connected therewith, said perforated pipes being connected to 75 said valve to open into said space only when they occupy the lower portion of the drum, during the rotation thereof.

5. Extracting apparatus comprising a horizontal rotary drum having at one end a 80 connection for introducing solvent, and means for introducing hot gas during the rotation of the drum, only within that portion of the drum which is at any moment lowermost, and having at the other end an 85 axially connected outlet.

6. Extracting apparatus comprising a horizontal rotary drum having at one end a connection for introducing solvent, and means for introducing hot gas, during the 90 rotation of the drum, only within that portion of the drum which is at any moment lowermost, and having adjacent the other end a filter, extending transversely of the drum and secured thereto, and beyond the 95 filter an axially connected outlet.

This specification signed and witnessed this 25th day of September, 1917.

WILLIAM E. GARRIGUES.

Correction in Letters Patent No. 1,282,407.

It is hereby certified that in Letters Patent No. 1,282,407, granted October 22, 1918, upon the application of William E. Garrigues, of New Orleans, Louisiana, for an improvement in "Apparatus for Extracting Soluble Substances," an error appears in the printed specification requiring correction as follows: Page 3, line 25, claim 1, for the word "or" read *for*; and that the said Letters Patent should be read with this correction therein that the same may conform to the record of the case in the Patent Office.

Signed and sealed this 24th day of December, A. D., 1918.

[SEAL.]

F. W. H. CLAY,

Acting Commissioner of Patents.
